UNITED STATES PATENT OFFICE.

JOHN A. LIEB, OF NEWARK, NEW JERSEY.

DESIGN FOR A BRACELET.

SPECIFICATION forming part of Design No. 11,664, dated March 2, 1880.

Application filed December 17, 1879. Term of patent 3½ years.

To all whom it may concern:

Be it known that I, JOHN A. LIEB, of Newark, county of Essex, and State of New Jersey, have originated and designed a Pattern for 5 Bracelets or like articles, of which the following is a full, clear, and exact description, reference being had to the accompanying drawing, which represents a face view of my design.

My design is applicable to bracelets or napkin-rings; and it consists of twolapping annular parallel arrangements of crossing oblique bars pivoted together at their ends and centers after the fashion of the device known as "lazy-tongs," the bars of each of said arrangements overlapping and pivoted to the bars of the other, so as to present the appearance of two annular lazy-tongs, the salient angles of which, at one side of each, overlap those of the other as far as the centers of the spaces in- 20 closed by the bars.

In the drawing, the letter A indicates an arrangement of a double series of oblique bars crossing each other and pivoted together at their ends and centers, and the letter A' designates a 25 similar arrangement of bars, the salient angles b of one of said arrangements overlapping the salient angles b' of the other, and the crossing bars of the separate arrangements are pivoted together at c. The angles of each arrangement 30 of bars extend to the centers of the spaces inclosed by the bars of the other arrangement;

and while the bars which incline in one direction are on the outside of those which they cross and to which they are pivoted, those which incline in the opposite direction are, of course, on the inside, so that the whole has the effect of being interlaced. By the overlapping and pivoting together of these two lazy-tongs arrangements of oblique bars I obtain a novel and readily distinguishable design applicable 40 to bracelets or napkin-rings.

I am aware that a single annular lazy-tongs arrangement of bars has been used for a bracelet, and also for a finger-ring, and such I do not claim.

What I claim as new, and desire to secure by Letters Patent, is—

The design for a bracelet or similar article of jewelry, the same consisting of the two parallel annular oblique bars overlapping each other 50 laterally and pivoted together where their bars cross each other, the salient angles of one extending to the centers of the inclosed spaces of the other, substantially as described, and shown in the accompanying drawing.

In testimony that I claim the foregoing I have hereunto set my hand and seal this 10th day of December, 1879.

JOHN A. LIEB. [L. S.]
